AQUARIUM STAND

Gerald R. Ritzow, 8844 Douglas Ave., Racine, Wis.
53402, and Roger C. Ritzow, S53 W23581 Big Bend
Road, Waukesha, Wis. 53186

Filed Apr. 25, 1973, Ser. No. 354,188

Term of patent 14 years

Int. Cl. D30—02

U.S. Cl. D30—12

FIG. 1 is a top plan view of an aquarium stand showing our new design;

FIG. 2 is an elevational view taken along line 2—2 of FIG. 1; and

FIG. 3 is an elevational view taken along line 3—3 of FIG. 1.

We claim:

The ornamental design for an aquarium stand, substantially as shown and described.
